Primary Examiner—Jeffrey Asch*(74) Attorney, Agent, or Firm*—Randall S. Vaas**CLAIM**

The ornamental design of an interface for communication devices or similar articles, as shown.

DESCRIPTION

FIG. 1 is a perspective view of an ornamental design of an interface for a communication device and similar articles; and,

FIG. 2 is a front elevation view thereof.

The broken line portions of the drawings form no part of the claimed design.
